(57) **CLAIM**

The ornamental design for a tool cradle, as shown and described.

DESCRIPTION

FIG. 1 is a top isometric view of the front right side of a tool cradle in accordance with an embodiment of the invention; FIG. 2 is a right side elevation view of the tool cradle of FIG. 1;

FIG. 3 is a left side elevation view of the tool cradle of FIG. 1;

FIG. 4 is a top plan view of the tool cradle of FIG. 1;

FIG. 5 is a bottom plan view of the tool cradle of FIG. 1;

FIG. 6 is a front end elevation view of the tool cradle of FIG. 1;

FIG. 7 is a back end elevation view of the tool cradle of FIG. 1;

FIG. 8 is a top isometric view of the back right side of the tool cradle of FIG. 1;

FIG. 9 is a bottom isometric view of the front right side of the tool cradle of FIG. 1; and,

FIG. 10 is a top isometric view of the front left side of the tool cradle of FIG. 1.

The components shown in broken lines in the drawings are for illustrative purposes only and do not form a part of the claimed design.
